Primary Examiner — Melanie H Tung(74) *Attorney, Agent, or Firm* — Fiala & Weaver P.L.L.C.**CLAIM**

The ornamental design for a graphical user interface for a display screen or a portion thereof, as shown and described.

DESCRIPTION

The text from the article entitled “Sony off to races with Gran Turismo” shown in FIG. 1 is subject to copyright protection. The copyrighted material is the property of its respective owner.

FIG. 1 is a front view of a graphical user interface for a display screen or portion thereof showing our new design;

FIG. 2 is a front view of a second embodiment thereof; and, FIG. 3 is a front view of a third embodiment thereof.

The broken line showing of the display screen or portion thereof in the figures is not part of the claimed design.

1 Claim, 2 Drawing SheetsFIG. 1

FIG. 2

FIG. 3
